FRANK E. CHASE, OF TONAWANDA, NEW YORK, ASSIGNOR OF ONE-FOURTH TO JAMES H. MUNDIE, OF NORTH TONAWANDA, NEW YORK.

POOL-BALL FRAME.

Specification of Letters Patent.

Patented Feb. 11, 1913.

1,052,461.

Application filed March 9, 1912. Serial No. 682,604.

To all whom it may concern:

Be it known that I, FRANK E. CHASE, a citizen of the United States, residing at Tonawanda, in the county of Erie and State of New York, have invented new and useful Improvements in Pool-Ball Frames, of which the following is a specification.

This invention relates to a frame or triangle for setting up the balls on a pool table. 10 As heretofore constructed these frames or triangles were provided with a ball receiving space or opening which was somewhat larger than the pyramid of balls intended to be placed within the frame and the inner 15 sides of the walls or bars of these frames were usually vertical. A frame of this construction does not permit of reliably setting up the balls so that they bear firmly against each other in a manner commonly known as 20 "frozen" and it is also difficult to remove the frame from the balls after they are set up without disturbing them, thereby preventing a player from getting the full benefit of his skill.

25 It is the object of this invention to provide a pool ball frame or triangle of simple and inexpensive construction which permits of quickly and accurately setting up the balls on the table so that they are always 30 frozen tight against each other and which avoids the liability of disturbing the balls while removing the frame after the balls have been set up.

In the accompanying drawings: Figure 1 35 is a top plan view of a pool ball frame or triangle embodying my invention. Fig. 2 is a vertical transverse section thereof taken in line 2-2, Fig. 1. Fig. 3 is a vertical section, on an enlarged scale, taken in line 3-3,

40 Fig. 2. Similar characters of reference indicate corresponding parts throughout the several views.

In its general organization the frame or 45 triangle is like that now in common use and comprises two forwardly converging side bars 1, 1 which are rigidly connected at their front ends and a rear cross bar 2 which is rigidly connected at its opposite ends with 50 the rear ends of the side bars so as to form a rigid triangle.

Arranged transversely within the triangular space or opening of the frame and lengthwise in front of the rear cross bar 3 where- 55 thereof is a follower or presser bar 3 where-

by the pyramid or body of balls may be pushed forwardly or toward the side bars and caused to bear firmly against each other or "freeze" together. This follower is pivotally connected with the rear cross bar 60 of the frame so that the same can swing in a vertical plane. The preferred means for this purpose consists of two pairs of hinges 4 secured to the lower edges of the rear cross bar of the frame and the follower, leaving 65 the upper edge of the latter free to move forwardly and backwardly lengthwise of the frame.

The follower is yieldingly held in its retracted or inoperative position against the 70 front side of the rear cross bar for which purpose various means may be used but those shown in the drawings are preferred and comprise a horizontal opening 5 formed in the central part of the rear cross bar of 75 the frame, a horizontal opening 6 formed in the follower and coinciding with the opening in the rear cross bar, and a spring 7 arranged in said openings and connected at their opposite ends, respectively, with the 80 rear cross bar and the follower. The connection between the spring and the follower preferably consists of a nail 8 driven into the follower and receiving the inner 85 end of the spring, and the connection between this spring and the cross bar preferably comprises a cap 9 which is inserted in the outer end of the outer opening and having an eye 10 to which the outer end of the 90 spring is attached.

Normally the follower is in its retracted vertical position, as shown in Figs. 1 and 3. After the balls have been placed upon the table within the frame the operator pushes the free upper edge of the follower forwardly and into engagement with the rear-most row of balls so that the entire body of balls is crowded or pushed forwardly into the forwardly tapering space of the frame and all the balls are caused to engage firmly 100 against each other. In order to permit the operator to thus push the follower forwardly the upper edge of the same projects a sufficient distance above the upper edge of the rear cross bar, as shown at 11 in Figs. 105 2 and 3, so as to enable the operator while holding the frame at its opposite rear corners by both hands to engage the thumbs of the hands with the upper edge of the follower and push the same forwardly into the 110

position shown by dotted lines in Figs. 1 and 3. After the follower has been thus pushed forwardly the same is released and permitted to swing back into its normal position from the rearmost row of balls to the rear side of the cross bar under the action of the spring. The frame is then lifted from the table leaving the balls on the table in the form of a perfect pyramid or triangular group in which each of the balls is properly frozen or engaged with adjacent balls.

10 The height of the bars of the frame is equal to about the radius of the pool balls so that the upper edges of the side bars engage with the balls of the outer rows about midway of their height.

15 Heretofore the inner sides, faces or walls of pool ball frames have usually been made vertical which is objectionable inasmuch as when lifting such a frame from the table with the balls after the latter have been set up the same are liable to be engaged frictionally by the inner sides of the side bars and disturbed or displaced slightly so that 25 they do not engage one another properly and thereby prevent a player from getting the full benefit of his skill.

20 In order to avoid disturbing the balls while lifting the frame after the balls have been set up, the inner sides, faces or walls of the side bars are beveled so that the opposing inner faces of the two side bars diverge downwardly, as shown in Fig. 2. By this means the two side bars only engage 35 with the outer rows of balls at the upper inner corners of the side bars and when lifting this frame subsequent to setting up the balls the frame clears itself from the balls owing to the gradual downward enlargement or flare of the opening within the 40 frame, whereby the frame is retained out of contact with the balls and displacement of the latter at this time is avoided.

45 This construction of pool ball frame is very simple and comparatively inexpensive, the same can be very easily manipulated and as there are no parts which project out-

side of the periphery of the frame there is no liability of interference with the ball pressing device and the frame can be stored 50 away as compactly as the frames now in common use.

I claim as my invention:

1. A rigid pool ball frame having all of its bars arranged to extend below the top 55 of the balls while the latter are within the frame and resting on the table, and a follower arranged adjacent to the inner side of one of the frame bars and pivotally connected therewith so as to be capable of 60 swinging vertically.

2. A rigid pool ball frame having all of its bars arranged to extend below the top of the balls while the latter are within the frame and resting on the table, a follower 65 arranged adjacent to the inner side of one of the frame bars and pivotally connected therewith so as to be capable of swinging vertically, and a spring for holding the follower 70 yieldingly in its retracted position.

3. A pool ball frame comprising side bars and a rear bar and a follower arranged transversely within the frame and in front of the rear bar and pivotally connected at its lower edge with the lower edge of said 75 rear bar so as to swing vertically.

4. A pool ball frame comprising two forwardly converging side bars, a rear cross bar provided with a horizontal opening, a follower arranged transversely within the 80 frame in front of the cross bar and provided with a horizontal opening in line with the opening of said cross bar, hinges connecting the lower edges of the cross bar and follower, and a spring arranged in said openings and connected with said cross bar and follower.

Witness my hand this 7th day of March, 1912.

FRANK E. CHASE.
